UNITED STATES PATENT OFFICE.

JOHN EDWARD KELLEY, OF LARCHMONT, AND BENNO F. JANCKE, OF NEW YORK, N. Y., ASSIGNORS TO EASTERN LABORATORIES, INC., OF NEW YORK, N. Y., A CORPORATION OF NEW YORK.

DESIGN FOR A CASING FOR A HAIR DRIER.

Application filed January 26, 1929. Serial No. 29,791. Term of patent 14 years.

To all whom it may concern:

Be it known that we, JOHN E. KELLEY and BENNO F. JANCKE, citizens, respectively, of the United States of America and Republic of Germany, and residing, respectively, at Larchmont, county of Westchester, State of New York, and borough of Kings, city and State of New York, have invented a new, original, and ornamental Design for a Casing for a Hair Drier, of which the following is a specification, reference being had to the

accompanying drawing, forming part thereof.

Figure 1 is a rear elevation of a casing for a hair drier showing our new design; Fig. 2 is a side elevation; and Fig. 3 is a front elevation.

We claim:—

The ornamental design for a casing for a hair-drier, as shown.

JOHN EDWARD KELLEY.
BENNO F. JANCKE.
